(57) **CLAIM**

The ornamental design for an elastic band toy launcher with bow configuration, as shown and described.

DESCRIPTION

FIG. 1 is a top perspective view of an elastic band toy launcher with bow configuration;

FIG. 2 is a rear view thereof;

FIG. 3 is a front view thereof;

FIG. 4 is a top view, the bottom view being a mirror image thereof;

FIG. 5 is a left side view thereof; and,

FIG. 6 is a right side thereof.

Portions of the disclosure shown in broken lines form no part of the claimed design.
